UNITED STATES PATENT OFFICE.

ARTHUR A. KATZ AND CHRISTIAN H. COOK, OF CHICAGO, ILLINOIS.

TEETH-CLEANING DEVICE.

Application filed March 15, 1926. Serial No. 94,842.

Our invention relates to devices for cleaning teeth and has among its other objects the production of devices of the kind described, which are convenient, compact, durable, efficient and satisfactory for use wherever found applicable.

A particular object of the invention is to produce an improved device of the kind described for cleaning both the exposed surfaces of the teeth and the interstices between the teeth.

One form of the invention is embodied in a device comprising a handle to which a brush is detachably secured so that it may be renewed. The handle is provided with a chamber or the equivalent adapted to hold a supply of dental floss which may be withdrawn from the chamber as desired, means being provided to hold the dental floss taut when in use.

Many other objects and advantages of the construction herein shown and described will be obvious to those skilled in the art from the disclosure herein given.

To this end our invention consists in the novel construction, arrangement and combination of parts herein shown and described, and more particularly pointed out in the claims.

In the drawings, wherein like reference characters indicate like or corresponding parts:

Fig. 1 is a central longitudinal section through a device embodying our invention;

Fig. 2 is a section taken on line 2—2 of Fig. 1;

Fig. 3 is a fragmentary view in elevation of the improved device;

Figs. 4, 5, 6, 7 and 8 are sections taken on lines 4—4, 5—5, 6—6, 7—7 and 8—8, respectively, of Fig. 1;

Fig. 9 is a central longitudinal section through the device embodying another form of our invention; and

Figs. 10, 11 and 12 are sections taken on lines 10—10, 11—11 and 12—12, respectively, of Fig. 9.

Referring for the present to Figs. 1 to 8, inclusive, wherein we have shown a device embodying a preferred form of the invention, 10 is a handle formed of any suitable material. Screw-threaded into one end of the handle 10 is a post 11 preferably formed integral with a tooth brush holder 12, the brush holder 12 being provided with an undercut groove 13 adapted to accom-

modate a backing member 14 from which bristles 15 project. As best shown in Fig. 1, the outer end of the groove 13 is closed by an end wall 17 formed integral with the brush holder 12. The other end of the groove 13 is normally closed by the handle 10. Obviously, the tooth brush may be replaced at any time if the brush holder 12 is first unscrewed from the handle 10. Another advantage of this construction is that other devices may be secured to the handle 10 in place of the brush. Thus, a safety razor having a post substantially identical to the post 11 may be secured to the handle if it is so desired.

The other end of the handle 10 is preferably tubular to provide a chamber 19 in which a bracket member 20 is slidably journaled. The inner end of the bracket member 20 is also tubular and provides a chamber 21 adapted to hold a supply of dental floss, which is indicated at 23. The bracket member 20 is preferably formed with a lateral extension 24 which may be brought into close proximity with a lateral extension 25 formed upon the handle 10 or the bracket member 20 may be moved into a plurality of adjusted positions with respect to the handle 10, such as, for instance, the dotted line position wherein it is shown in Fig. 1. The bracket member 20 may be secured in these adjusted positions by means comprising a spring member 27 carried by or formed integral with the handle 10, the spring member 27 being provided with a tooth 28 adapted to engage notches 29 formed in the bracket member 20. We preferably provide a relatively small knob 30 upon the spring member 27 so that the spring member may be readily flexed to bring the tooth 28 out of engagement with any one of the notches 29.

As best shown in Fig. 6, the tooth 28 prevents rotation of the bracket member 20 around the longitudinal axis of the handle 10. The tubular end of the bracket member 20 is preferably slotted as at 32 so that the dental floss may be withdrawn therefrom, the slot 32 preferably registering with a slot 33 formed in the tubular end of the handle 10. Projecting from the bracket member 20 and normally disposed in the slot 33 are a plurality of lugs 35, the purpose of which will presently appear. The outer ends of the extensions 24 and 25 are

preferably provided with slots 37 and 38, respectively, or the equivalents, for the pur-

90

95

100

105

110

pose. The slots 37 and 38 may be of any desired form but are preferably substantially S-shaped.

When the dental floss 23 is to be used, a length thereof is withdrawn through the slots 32 and 33 and passed through the substantially S-shaped slots 37 and 38, a suitable length of floss for use being left between the slots 37 and 38. The bracket member 20 is then brought into the position wherein it is shown in dotted lines in Fig. 1. This draws the floss, the bracket member being held in its extended position by the tooth 28 carried by the spring member 27. After the length of floss or thread disposed between the slots 37 and 38 has been used, it is withdrawn from these slots and a few turns thereof are wound around the lugs 35. The lugs 35 are so formed that if tension is then applied to the used end of the floss, the lugs will sever the used portion from the unused portion. The bracket member 20 is then returned to the position wherein it is shown in full lines in Fig. 1.

In Figs. 9 to 12, inclusive, we have illustrated another form of the invention embodied in a device which comprises a curved handle 10^a. Screw-threaded into one end of the curved handle 10^a is a lug 11^a formed integral with a brush holder 12^a. The brush holder 12^a is preferably formed from sheet metal stamped to provide oppositely disposed grooves 13^a which are adapted to accommodate flanges 13^b formed integral with a backing member 14^a from which bristles 15^a project. The backing member 14^a and the bristles 15^a constitute a brush for cleaning the readily accessible surfaces of the teeth. The brush holder 12^a is provided with a flange 17^a which cooperates with the handle 10^a to retain the backing member 14^a in place.

Screw-threaded, or otherwise secured to the other end of the handle 10^a, is a tubular handle member 10^b having a chamber 19^b adapted to hold a supply of dental floss which is indicated at 23^b. A slot 33^a formed in the handle member 10^b permits the dental floss to be withdrawn from the chamber 19^b.

Screw-threaded into, or otherwise detachably secured to the handle member 10^b, is a handle member 10^c in which a bracket member 20^a is slidably journaled. The handle member 10^c is formed with a spring member 27 carrying a tooth 28^c adapted to engage notches 29^a formed in the bracket member 20^a. The bracket member 20^a is formed with a lateral extension 24^a adapted to be brought into close proximity to a lateral extension 25^a formed upon the handle member 10^c. The outer ends of the extensions 24^a and 25^a are preferably slotted as at 37^a and 38^a, respectively, the slot 37^a being cut in a ball 37^b preferably formed upon the

extension 24^a. A bent pin or lug 35^a projects from the lateral extension 25^a and may be used for the same purpose as the aforementioned lugs 35.

The device illustrated in Figs. 9 to 12, inclusive, is used in substantially the same manner as the device illustrated in Figs. 1 to 8, inclusive. Thus, the dental floss 23^b may be withdrawn from the handle member 10^b through the slot 33^a. The portion of dental floss so withdrawn from the handle member 10^b may be secured in the slots 37^a and 38^a after which the bracket member 20^a may be brought into an extended position with respect to the handle member 10^c. This will draw the dental floss taut between the extensions 24^a and 25^a. If desired, the free end of the dental floss may be secured to the extension 24^a by wrapping it around the extension underneat the ball 37^b.

Having thus described our invention, it is obvious that various immaterial modifications may be made in the same without departing from the spirit of our invention; hence we do not wish to be understood as limiting ourselves to the exact form, construction, arrangement and combination of parts herein shown and described or uses mentioned.

What we claim as new and desire to secure by Letters Patent is:

1. A device of the kind described comprising a handle having a chamber adapted to hold dental floss, said handle being adapted to have said floss secured thereto, and means slidably journaled in said handle and adapted to have said floss secured thereto.

2. A device of the kind described comprising a handle adapted to hold dental floss and adapted to have said floss secured thereto, means adjustable with respect to said handle and adapted to have said floss secured thereto, and resilient means for securing said last-mentioned means in a plurality of adjusted positions with respect to said handle.

3. In a tooth brush a handle having a chamber, a bracket slidable in the chamber to hold dental floss, a lateral extension on the handle at one end of the chamber, and means for retaining said bracket in a plurality of adjusted positions with respect to the handle.

4. In a tooth brush, a handle having a chamber, an angular bracket having a tubular portion slidable in the chamber to hold dental floss, a lateral extension on the handle, a lateral extension on the bracket lying parallel with the first extension, said extensions adapted to have said dental floss secured thereto, and means for retaining said bracket in a plurality of adjusted positions with respect to the handle.

5. In a tooth brush, a handle having a

chamber, an angular bracket having a tubular portion slidable in the chamber to hold dental floss, a lateral extension on the handle, a lateral extension on the bracket lying parallel with the first extension, said chamber and tubular portion having registering slots through which the floss is passed, said extensions adapted to have said floss secured thereto, and means for retaining said bracket in a plurality of adjusted positions with respect to the handle.

6. In a tooth brush, a handle having a chamber, an angular bracket having a tubular portion slidable in the chamber to hold dental floss, a lateral extension on the handle, a lateral extension on the bracket lying parallel with the first extension, said

chamber and tubular portion having registering slots through which the floss is passed, lugs carried by the bracket and disposed in the slot therein, said extension adapted to have said floss secured thereto and means for retaining said bracket in a plurality of adjusted positions with respect to the handle.

7. In a tooth brush, a handle having a chamber, a bracket slidable in the chamber to hold dental floss, and means for retaining said bracket in a plurality of adjusted positions with respect to the handle.

In testimony whereof, we have hereunto signed our names.

ARTHUR A. KATZ.
CHRISTIAN H. COOK.
